UNITED STATES PATENT OFFICE.

JAMES B. REPLOGLE, OF DETROIT, MICHIGAN, ASSIGNEE TO THE REMY ELECTRIC COMPANY, A CORPORATION OF INDIANA.

INDUCTION-COIL

1,401,493.

Specification of Letters Patent Patented Dec. 27, 1921.

Application filed June 13, 1919. Serial No. 303,829.

To all whom it may concern:

Be it known that I, JAMES B. REPLOGLE, a citizen of the United States of America, residing at Detroit, county of Wayne, State of Michigan, have invented certain new and useful Improvements in Induction-Coils, of which the following is a full, clear, and exact description.

This invention relates to induction coils and has among its objects the production of an induction coil of maximum efficiency in operation with the smallest possible cost.

In carrying out this aim of the invention it is a further object of the invention to provide an improved method of coil construction whereby the cost of production will be minimized.

Other and further objects and advantages of the present invention will be apparent from the following description, reference being had to the accompanying drawings, wherein preferred embodiments of the present invention are clearly shown.

In the drawings:

Figure 1 is a longitudinal sectional view of an ignition coil embodying the present invention.

Fig. 2 is a sectional view taken on the line 2—2 of Fig. 1.

Fig. 3 is an end view of the coil housing.

Fig. 4 is a perspective view of the coil core in the initial stage of assembly.

Fig. 5 is a perspective view of the coil windings which are formed before assembling upon the core; and

Fig. 6 is a perspective view of the core showing the manner in which certain of the laminated portions of the core are bent from their normal position in order to permit the assembling of the coil upon the core.

In the drawings, 20 designates the ignition coil core which includes a base portion 21, and projecting through said base, a straight leg 22 and L-shaped legs 23 and 25 having their outer free ends 24 and 26 respectively arranged to face in toward the outer free end of the straight leg 22. These ends 24 and 26 are spaced from the leg 22 in order to provide air gaps 27 and 28.

The core 20 consists of a plurality of superimposed laminations each formed in the manner described, and these laminations are secured together at the base portion by means of a channel member 30 of non-magnetic material which clamps together the

base portions of said laminations and is held in position by means of rivets 31 and 32.

The coil portion designated as a whole by numeral 35 includes a tube of insulation 36 about which is wound the primary winding 37. Winding 37 is surrounded by a tube of insulation 38 about which is wound the secondary winding 39. The ends and outer cylindrical surface of the coil 39 are inclosed by wrappings of insulating material 40, 41 and 42.

In order to assemble the coil 35 upon the straight leg 22 and laminæ composing the L-shaped legs 23 and 25 are spread apart and bent away from the straight leg as shown in Fig. 6. When the clearance between the ends 24 and 26 in the outer end of the leg 22 is sufficient, the coil 35 may be assembled upon the straight leg 22 in the position shown in Fig. 1. After this operation has been performed the laminæ composing legs 23 and 25 are bent back again into the normal position shown in Fig. 4 and are clamped together in this position by means of a channel member 45, which surrounds the outer free ends of the leg members 22, 23 and 25 and is secured in position by means of rivets 46, 47 and 48.

The coil is now ready for assembly within the coil housing. This housing consists of a channel shaped base member 50 upon the under side of which is secured a bracket 51 by means of which the coil housing may be attached to any suitable support. To the flanges of the base 50 are secured the ends of the intermediate section 52 of the housing which is U-shaped in section and is constructed preferably of non-conducting material. The housing includes end sections 53 and 54 which are formed and provided with flanges 55 and 56, respectively, so as to fit over the end edges of the intermediate section 52 and the end edges of the base member 50. The channel member 30 is attached to the end 53 by means of screws 57, and the channel member 45 is secured to the end 54 by means of screws 58. In this manner the core 20 together with the channel members 30 and 45 serve as a tie member for tying together the intermediate end portions of the housing, while the channel members 30 and 45 serve as means for supporting the coil within the housing.

Where the induction coil is used in connection with ignition apparatus in which a

condenser is employed, this condenser may be inclosed within the housing described. In the embodiment of the invention shown the condenser is inclosed within a condenser case 60 which is supported within the housing upon the base portion 50.

The intermediate section 52 supports a high tension terminal 61 to which one end of the secondary winding 39 is attached, the other end being grounded in any suitable manner. The ends of the primary winding 37 are connected in any suitable manner with terminals 62 and 63 which are mounted upon the end member 54. Where the induction coil is used for ignition purposes, one of these primary terminals may be connected with the ignition timer and the other with a source of current.

Non-conducting channel members 64 and 65 may be used further to insulate the windings from the core.

It has been found that by constructing the induction coil core in the manner described that the efficiency of the coil is greatly increased by reason of the fact that the greatest number of flux lines are made to encircle the turns of the coil windings, and that the number of flux lines which are ineffective has been reduced to a minimum. In the embodiment of the invention shown the core is provided with two L-shaped legs which face in toward the straight leg about which the coil is arranged. In this manner two magnetic circuits each having an air gap encircle the turns of the coil windings. In providing for an air gap in the magnetic circuit in order to introduce a given reluctance in the circuit, it is advantageous to have the area of the gap as great as possible in order that the distance across the gap or length of gap may be proportionally large. If the length of gap is relatively large, then relatively slight variations in the dimensions of the laminations are permissible since the reluctance of the circuit will not be so materially affected as where the gap is relatively short. Hence the desired length of gap may be maintained fairly accurately without requiring actual machining of the core after the core laminations have been assembled. In order to secure proper amount of gap area it has been found preferable, from the standpoint of economy of space and economy in the amount of material required to the core, to provide a plurality of gaps having a combined area equal to the area required to provide the necessary reluctance. In this manner the distance across the gaps may be made sufficiently great so that the reluctance will not be materially affected by any variations in the dimensions of the punched laminations which compose the core.

The method of assembling the coil upon the core which has been described permits the formation of the core of a series of punched laminations all of the same size. If this method of assembly were not resorted to it would be necessary to form certain parts of the core separately from the others, as for example, to build up the L-shaped legs separately from the base of the core and assemble these L-shaped legs in position upon the base after the coil has been placed in position upon the straight leg. It is obvious that it is more economical to form the core of a series of laminations all of the same shape and dimensions rather than to provide for sets of punchings which vary in shape and dimensions.

While the form of mechanism herein shown and described constitutes a preferred form of embodiment of the invention, it is to be understood that other forms might be adopted, all coming within the scope of the claims which follow.

I claim:

1. In an induction coil, the combination with primary and secondary windings; of a core including a base portion and integral branch portions providing two magnetic circuits threading said windings and each magnetic circuit being provided with an air gap having a substantially greater area than the sectional area of the base portion.

2. In an induction coil, the combination with primary and secondary windings; of a core including a base portion, a straight leg extending from said base portion and through and beyond said windings, and L-shaped legs extending from the base portion and located outside said windings and facing in toward the straight leg but spaced therefrom to provide air gaps, the portions of the L-shaped legs thus facing in each having a sectional area greater than the sectional area of the base portion or other portions of the L-shaped legs.

3. In an induction coil, the combination with primary and secondary windings; of a core comprising a base portion, a straight leg and a plurality of L-shaped legs extending from the base, said L-shaped legs being arranged to face in toward the straight leg but spaced therefrom to form air gaps in the magnetic circuits adjacent the free end of the straight leg, the area of said air gaps being substantially greater than either the sectional area of the base portion or the sectional area of the portions of the L-shaped legs adjacent the base portion.

4. In an induction coil, the combination with primary and secondary windings; of a core upon which said windings are mounted; and a housing for said core and windings comprising end members and an interme-

diate portion; and means for attaching said core to the end members whereby the intermediate portion is held in position between the end members and the coil is supported within the housing.

5. In an induction coil, the combination with primary and secondary windings; of a core upon which said windings are mounted, said core including a plurality of laminations which are held together along opposite edges of channel members; a housing for the coil including end members and an intermediate portion; and means for attaching said channel members to the end members of the housing whereby the intermediate portion is held in position between the end portions and

the core is held in position within the housing.

6. In an induction coil, the combination with a housing including an intermediate member and end members; of means for securing said members together including a core, and members for attaching each end of said core to an adjacent end member of said housing; and windings supported by said core.

In testimony whereof I affix my signature.

JAMES B. REPLOGLE.
